Primary Examiner—Cathron C. Brooks*Assistant Examiner*—Austin Murphy(74) *Attorney, Agent, or Firm*—Michael P. Leary; Charles E. Yocum; Adan Ayala(57) **CLAIM**

The ornamental design for power shears, as shown and described.

DESCRIPTION

FIG. 1 is a perspective view of power shears showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines shown in the drawings form no part of the claimed design.
